UNITED STATES PATENT OFFICE

168,446

COMBINATION TELEVISION CHAIR AND
TABLE UNIT

Robert Hall, Philadelphia, Pa.

Application February 28, 1952, Serial No. 13,701

Term of patent 14 years

(Cl. D15—1)

To all whom it may concern:

Be it known that I, Robert Hall, a citizen of the United States, residing at Philadelphia, in the county of Philadelphia and State of Pennsylvania, have invented a new, original, and ornamental Design for a Combination Television Chair and Table Unit, of which the following is a specification, reference being had to the accompanying drawing, forming part thereof.

In the drawing:

Fig. 1 is a front perspective view of a combination television chair and table unit showing my new design.

Fig. 2 is a rear perspective view of the unit shown in Fig. 1.

Fig. 3 shows the unit in open position.

Fig. 4 is a front view of the unit.

Fig. 5 is a rear view of the unit in open position.

Fig. 6 is a side view of the unit in open position.

Fig. 7 is a bottom plan view of the unit in open position as taken on line 7—7 of Fig. 5.

I claim:

The ornamental design for a combination television chair and table unit, substantially as shown.

ROBERT HALL.
